CANDY PACKAGE

Alfred Ross, Brooklyn, N. Y.

Application April 13, 1954, Serial No. 29,983

Term of patent 3½ years

(Cl. D58—2)

To all whom it may concern:

Be it known that I, Alfred Ross, a citizen of the United States, residing at Brooklyn, in the county of Kings, and State of New York, have invented a new, original, and ornamental Design for a Candy Package, of which the following is a specification, reference being had to the accompanying drawing, forming part thereof.

In the drawing:

Fig. 1 is a top plan view of a candy package, showing my new design;

Fig. 2 is a side elevational view thereof;

Fig. 3 is a bottom plan view thereof;

Fig. 4 is a cross-sectional view thereof, taken on the line 4-4 of Fig. 1; and

Fig. 5 is a cross-sectional view thereof, taken on the line 5-5 of Fig. 4.

I claim:

The ornamental design for a candy package, as shown.
